Primary Examiner — Anhdao Doan(74) *Attorney, Agent, or Firm* — Womble Bond Dickinson (US) LLP(57) **CLAIM**

The ornamental design for a biostimulator loading tool, as shown and described.

DESCRIPTION

FIG. 1 is a side perspective view of a leadless biostimulator loading tool showing our new design;

FIG. 2 is a front elevation view thereof;

FIG. 3 is a rear elevation side view thereof;

FIG. 4 is a right side view thereof;

FIG. 5 is a left side view thereof;

FIG. 6 is a an alternative left side view thereof in a locked configuration;

FIG. 7 is a top view thereof;

FIG. 8 is a bottom view thereof; and,

FIG. 9 is an alternative perspective view thereof.

The broken lines illustrate portions of the biostimulator loading tool that form no part of the claimed design; the broken lines form no part of the claimed design.
